(57) **CLAIM**

The ornamental design for a corkscrew stand, as shown and described.

DESCRIPTION

A tool and integrated stand for removing corks from bottles. FIG. 1 is a top right perspective view of a corkscrew stand according to my design;

FIG. 2 is a top left perspective view of a corkscrew stand according to my design;

FIG. 3 is a right side view thereof;

FIG. 4 is a back view thereof;

FIG. 5 is a front view thereof with expanded jaws;

FIG. 6 is a top plan view of the corkscrew stand; and,

FIG. 7 is a bottom plan view thereof.

The circular cross-hatched pattern represents a debossed area.
